UNITED STATES PATENT OFFICE.

RUDOLPH HOFFMAN, OF CHICAGO, ILLINOIS, ASSIGNOR TO SEARS, ROEBUCK AND COMPANY, OF CHICAGO, ILLINOIS, A CORPORATION OF NEW YORK.

OIL-STOVE.

1,094,149.

Specification of Letters Patent. Patented Apr. 21, 1914.

Application filed November 10, 1913. Serial No. 800,066.

To all whom it may concern:

Be it known that I, RUDOLPH HOFFMAN, a citizen of the United States, residing at Chicago, in the county of Cook and State of Illinois, have invented certain new and useful Improvements in Oil-Stoves, of which the following is a specification.

This invention relates particularly to improvements in oil reservoirs for oil-burning 10 cook stoves and ranges.

One of the objects of the invention is to provide improved means for removably supporting the reservoir.

Another object is to produce means for 15 connecting a carrying bail to a glass reservoir.

In the accompanying drawings, Figure 1 is a fragmental front elevation of an oil 20 stove provided with a reservoir embodying the features of my invention. Fig. 2 is a fragmental view taken from the right-hand side of Fig. 1. Fig. 3 is a fragmentary horizontal sectional view taken in the plane of dotted line 3—3 of Fig. 2.

In Fig. 1, 1 denotes a burner which may be of any suitable or preferred character, and 2 designates an end wall of the stove.

3 is a horizontally disposed member which is attached to the wall 2 by suitable 30 means such, for example, as an inclined connecting member 4. The parts 3 and 4 may be formed from an integral piece of sheet metal. The member 3 is supported in part by two arms 5 attached at their ends to 35 the outer corners of the member 4 and to the wall 2. Fixed to the member 4 and extending downwardly therefrom is a well 6, the lower end of which communicates with the burner 1 through the medium of a feed 40 pipe 7.

In the present embodiment of the invention, the oil tank 8 is of glass and comprises a cylindrical body 9 having a neck 10. The neck 10 is provided with suitable 45 means for closing it, such as a cap or closure 11 adapted to be screwed onto the neck. The closure 11 has an outlet opening 12 which may be arranged to be closed by any preferred means such as a valve 13 fixed to 50 a stem 14, said stem being guided by a standing loop 15. A spring 16 tends to move the valve 13 into position to close the opening 12. When the tank is in place, as shown in Fig. 2, the lower end of the stem 55 14 rests upon the bottom of the well 6,

thereby holding the valve 13 open. When the tank is lifted out of place, the spring 16 seats the valve 13. The tank 8 is arranged to be supported upon the arms 5, the latter being notched as at 17 to receive two diametrically opposite projections on the body 9. These projections may be of any suitable construction; herein I have shown them as each consisting of a flanged sheet metal member 18 secured by a bolt 19 and nut 20 to a band 21 that encircles the body 9. The band 21 may lie within an annular groove 22 in the body 9, as shown. The body 9 has a recess 9^a to receive the head of the bolt 19, said recess being of sufficient size to prevent a blow upon the flanged member 18 from driving the head of the bolt into contact with the glass. The portion of the band 21 which bridges the recess serves to cushion shocks received by the member 18. To prevent the band from shifting circumferentially of the tank, suitable means may, if desired, be used, such as the interlocking connection herein disclosed consisting of a lug 23 on the body 9 projecting into a cut-out or recess 24 in one edge of the band. The flanged members 18 are preferably slightly below the center of gravity of the tank when the latter is in operative position so that when the user takes hold of the bail and lifts the reservoir off its supports the reservoir shall turn through 180° into position to be filled. When the tank is in position for use, the neck 10 extends into the well 6.

In the present embodiment of the invention, the weight of the tank is carried by the arms 5, swinging movement (to right or left, Fig. 1) being prevented by bosses 25 on the member 3, which bosses are in position to come into contact with the neck 10.

26 is a carrying bail having loops 27 that are pivotally mounted on the flanged members 18.

Figs. 1 and 2 illustrate the tank in operative position, the outlet 12 being open, and the well 6 being partly filled with oil. When the user observes that the tank is nearly empty, she grasps the bail 26 and lifts the tank off from its supports 5, the valve 13 closing automatically, and the tank turning through 180°. The closure 11 is then unscrewed, a quantity of oil poured into the tank, the closure replaced, and the tank inverted and set on the arms 5.

I claim as my invention:

1. In an oil stove, a stove frame, a tank having a body and a neck, two diametrically opposite projections on said body intermediate the ends of the body, two supports on the stove frame, said projections resting upon said supports, and a well below the supports, the neck of the tank extending into said well.
- 10 2. In an oil stove, a stove frame, a horizontal member, means for securing said member to the stove frame, two arms connecting the outer portions of said member with the stove frame, a well attached to and depending from said member, and a tank arranged to rest upon said arms, said tank having an outlet portion extending into said well.
- 15 3. In an oil stove, a stove frame, a horizontal member, means for securing the inner portion of said member to the stove frame, two arms connecting the outer portions of said member to the stove frame, a well attached to said member, said arms

having notches in their upper edges, and a tank having diametrically opposite projections arranged to lie in said notches, said tank having an outlet portion extending into said well.

4. In an oil stove, a stove frame, a glass oil tank, metal projections secured to said tank intermediate its ends, supports on the stove frame on which said projections bear, and whereby said tank is supported, and a well into which the tank extends.

5. In an oil stove, a glass oil tank having a groove extending around it, a metal band in said groove, two metallic projections secured to opposite portions of said band, supporting means on which said projections rest, and means to prevent the tank from swinging on said supporting means.

In testimony whereof I affix my signature in presence of two witnesses.

RUDOLPH HOFFMAN.
